VALVE GRINDING APPARATUS

Eivind H. Jensen, Sarpsborg, Norway, assignor of one-half to Birger J. Jensen, San Diego, Calif.

Application November 10, 1958, Serial No. 772,798

4 Claims. (Cl. 51—241)

The present invention relates generally to grinding tools and more particularly to a valve grinding apparatus for valves having a diameter on the order of four inches and larger.

It is evident that the necessity for elimination of chatter and non-uniformity of pressure has not hitherto been fully recognized and the primary object of this invention is to provide a valve grinding apparatus which is attached directly to the body of the valve with absolute firmness and maintains the grinding element firmly in contact with the valve seat under adjustable, constant pressure and without the hitherto ignored chatter occasioned by prior art devices. Elimination of virtually all chatter is one of the principal features of this invention, the improvement attained being unexpectedly great, and is effected in part by introduction of a virtually frictionless bearing for one end of the spring employed to control grinding wheel pressure.

Another object of this invention is to provide a valve grinding apparatus in which the grinding element is universally mounted in a special manner to maintain uniform contact pressure with valve seats which are angularly offset from the axis of the grinder shaft.

Still another object of this invention is to provide a valve grinding apparatus which may be used to reseat many types of valves and is particularly effective with such large valves as those often encountered in ship chandlery, oil field operations and transmission lines for oil, gas, steam and water.

A further object of this invention is to provide a valve grinding apparatus which can be manually operated or power driven and which permits inspection of the work during the grinding operation without disturbing the original pressure setting.

Another object of this invention is to provide a valve grinding apparatus which is adapted for fabrication from many different materials, so that the choice of material can be according to the dictates of availability and price considerations, the exact sizes and proportions being matters easily determined to suit particular conditions and needs.

Another object of this invention is to provide a valve grinding apparatus which is practical and inexpensive to manufacture.

Finally, it is an object to provide a valve grinding apparatus of the aforementioned character which is simple and convenient to operate and which will give generally efficient and durable service.

With these and other objects definitely in view, this invention consists in the novel construction, combination and arrangement of elements and portions, as will be hereinafter fully described in the specification, particularly pointed out in the claims, and illustrated in the drawing which forms a material part of this disclosure, and in which:

Figure 1 is a side elevation view of the apparatus, a

2

valve structure being indicated fragmentarily in broken line;

Figure 2 is a sectional view taken on the line 2—2 of Figure 1; and

Figure 3 is a top plan view of the apparatus.

Similar characters of reference indicate similar or identical elements and portions throughout the specification and throughout the views of the drawing.

Referring now to the drawing in detail, the illustrative apparatus as disclosed in the drawing includes a mounting bracket 10 which supports the mechanism, a drive shaft 12 rotatably mounted in said bracket and a grinding disc 14 attached to the shaft. The mounting bracket 10 comprises an internally screw threaded collar 16 having two pairs of spaced parallel support bars 18 extending from diametrically opposite sides thereof, said support bars being welded or otherwise secured, with absolute firmness to said collar. Fitted into the collar 16 is an externally screw threaded bearing sleeve 20 which is axially adjustable and can be secured in any position by a lock nut 22. The drive shaft 12 is carefully fitted into the sleeve 20 and is freely rotatable and axially slideable in the sleeve 20 and has a conventional shank 24 at one end to fit a drive motor or hand crank for operating the device. At the other end of the drive shaft 12 is a flange 26 on which is a thrust bearing 28 concentric with the shaft, and fitted between said thrust bearing and the bearing sleeve 20 is a compression spring 30. Extending from the flanged end of the drive shaft 12 is a fork 32 in which is secured a universal coupling 34, that illustrated being a simple two-axis type, although ball joints or other types of universal joints may be used. Secured to the other end of the universal coupling 34 is a stub axle 36 having an enlarged boss 38 and a screw threaded portion 40 extending therefrom. The grinding disc 14 is mounted on the stub axle 36, against the boss 38, between two clamp washers 42 and is held by a retaining nut 44 on the screw threaded portion 40. The grinding disc 14 is illustrated as a simple flat disc for grinding flat faces, but various discs or other grinding elements of contoured shapes may be used, according to requirements.

The valve 46 illustrated in broken line in Figure 1 is a large valve having opposed seating rings 48 which serve as valve seats, this particular valve being shown merely as an example. The valve 46 has an inlet 50, or outlet 52 as the case may be, having an annular flange 52 to which the associated piping is attached, many types of valves being constructed in a similar manner. The valve grinding apparatus is mounted directly on the valve body and the flange 52 provides a convenient attachment portion, the mounting bracket 10 being held by suitable bolts 54 and nuts 56, the bolts passing through the existing bolt holes in said flange and being secured to the mounting bracket by large washers 58 resting across the support bars 18. In other types of valves, the mounting bracket 10 may be bolted or clamped in a suitable manner to a convenient part of the valve structure, the long support bars 18 providing ample means for attachment to valves of various sizes. If necessary, the grinding disc 14 can be attached after the mounting bracket and drive shaft assembly is bolted in position.

The grinding disc 14 is adjusted on its universal mounting to rest flat on the seating ring 48, after which the bearing sleeve 20 is screwed in or out in the collar 16 so that the spring 30 holds the grinding disc in place with the required working pressure, said sleeve then being secured by the lock nut 22. The drive shaft 12 may be rotated by hand to ensure proper seating of the grinding disc 14 before applying power to start the grinding operation. By using the universal mounting and having a constant working pressure, the grinding is accomplished

quickly and accurately. The valve seat may be inspected at any time by forcibly raising the drive shaft 12 against the pressure of spring 30, thus avoiding any disturbance of the pressure adjustment.

By supporting the mechanism directly on the valve body, accurate positioning and alignment is facilitated. It has been found that many types of valves can be treated while still installed in their working position, necessitating only partial dismantling of piping and valve structure for access to the valve seats.

The operation of this invention will be clearly comprehended from a consideration of the foregoing description of the mechanical details thereof, taken in connection with the drawing and the above recited objects. It will be obvious that all said objects are amply achieved by this invention.

It is understood that minor variation from the form of the invention disclosed herein may be made without departure from the spirit and scope of the invention, and that the specification and drawing are to be considered as merely illustrative rather than limiting.

I claim:

1. A valve grinding apparatus, comprising: a bearing sleeve; a shaft freely rotatable and axially slidable in said sleeve; a stub axle, a driving connection between said shaft and one end of said stub axle; a grinding element mounted on the other end of said stub axle; an anti-friction thrust bearing on said shaft remote from said sleeve; a spring on said shaft and compressed between said bearing and said sleeve and urging said grinding element and stub axle away from said sleeve; the other end of said shaft having means for connection to a source of power; and support means rigidly attached to said sleeve to secure the apparatus in working position on a valve body.

2. A valve grinding apparatus, comprising: a collar having support means fixed thereto for attachment to a valve body; a bearing sleeve axially adjustably mounted

in said collar; a shaft freely rotatable and axially slid- able in said sleeve; a stub axle universally mounted on one end of said shaft; a grinding element mounted on the end of said stub axle remote from said shaft; said shaft having an anti-friction thrust bearing thereon; a spring mounted on said shaft between said anti-friction thrust bearing and said sleeve and urging said grinding element away from said sleeve; the other end of said shaft having means for connection to a source of power.

10 3. A valve grinding apparatus, comprising: a collar having support means fixed thereto for attachment to a valve body; a bearing sleeve axially adjustably mounted in said collar; a shaft freely rotatable and axially slidable in said sleeve; one end of said shaft having a flange; a thrust bearing mounted against said flange; a compression spring on said shaft between said thrust bearing and said sleeve; a universal coupling secured to said one end; and a grinding element detachably secured to said universal coupling; the other end of said shaft having a shank portion for connection to a source of power.

15 4. A valve grinding apparatus, comprising: a collar; opposed pairs of spaced, parallel support bars fixed to said collar and extending from diametrically opposite sides thereof for attachment to a valve structure; said collar being internally screw threaded; an externally screw threaded sleeve axially adjustably mounted in said collar and locking means on said sleeve whereby the sleeve may be locked in adjusted position relative to said collar; a shaft freely rotatable and axially slidable in said sleeve; one end of said shaft having a flange; a thrust bearing mounted against said flange; a compression spring on said shaft between said thrust bearing and said sleeve; a universal coupling secured to said one end; and a grinding element detachably secured to said universal coupling; the other end of said shaft having a shank portion for connection to a source of power.
